(57) CLAIM

The ornamental design for a motor vehicle, as shown and described.

DESCRIPTION

FIG. 1 is a first perspective view of a motor vehicle;

FIG. 2 is a second perspective view thereof;

FIG. 3 is a front view thereof;

FIG. 4 is a right side view thereof;

FIG. 5 is a top view thereof;

FIG. 6 is an enlarged perspective view of FIG. 1 thereof;

FIG. 7 is an enlarged perspective view of FIG. 2 thereof;

FIG. 8 is an enlarged front view of FIG. 3 thereof;

FIG. 9 is an enlarged right side view of FIG. 4 thereof; and,

FIG. 10 is an enlarged top view of FIG. 5 thereof.

The portion shown by broken lines is for illustrative purposes only and forms no part of the claimed design.

The dashed lines show a boundary between the claimed design and unclaimed portions.
